UNITED STATES PATENT OFFICE.

ROE C. HAWKINS, OF LONG BEACH, CALIFORNIA.

AUTOMATIC ROTARY SCRAPER.

Application filed June 7, 1923. Serial No. 643,925.

To all whom it may concern:

Be it known that I, ROE C. HAWKINS, a citizen of the United States, residing at Long Beach, in the county of Los Angeles and State of California, have invented new and useful Improvements in Automatic Rotary Scrapers, of which the following is a specification.

My present invention is an automatic rotary scraper; and it is a special object of this invention to provide a scraper resembling the "Fresno" type with novel means to facilitate the loading and the gradual unloading or sudden dumping of the same.

It is an object of this invention to provide a scraper of the character referred to with means permitting at will either a complete rotation of the scraper bowl, in order to dump the contents in a single pile or, alternatively, a gradual or distributing or leveling delivery of the contents of said bowl, my preferred construction being such that the scraper may, however, be dragged any desired distance either with its bowl full or with its bowl inverted, and such that the bowl of my scraper may easily be positioned for filling, such positioning being effected without the necessity for any backing or other difficult movement.

It is an object of this invention to provide means whereby my scraper may be variously hitched, in accordance with the requirements of different tractors, or the like, or in accordance with the requirements of different soils or situations in which my scraper may be used; and the bowl of my scraper is preferably provided with wheel-like ends, and with pivots on said ends, said pivots being, in one embodiment of my invention, adapted to extend through slots in the frame by which my scraper may be drawn,—this frame being preferably so constructed as to provide bearings and guards for all operating parts.

It is a further object of this invention to provide a scraper comprising a comparatively simple frame and a simple bowl, which may be of known design except as hereinafter stated, and comparatively few and rugged operating parts, not unduly exposed to accidental derangement; and in a preferred construction I employ a single hand lever, within reach of the driver of a tractor by which my scraper may be drawn, and I may utilize a single pair of

springs, or the like, and suitable connections, either to cause the bowl of my scraper to pick up a load or to dump the same or to remain filled or remain empty during its advance to any desired distance.

Other objects of my invention will appear from the following description of alternative embodiments thereof, and from the appended claims, taken in connection with the accompanying drawings, in which—

Fig. 1 is a plan view of a scraper of my improved design.

Fig. 2 is a side elevation of the same, with parts shown in that relative position which they would occupy during the picking up of a load.

Fig. 3 is a similar view of my scraper, but showing the parts in those relative positions which they would occupy during the gradual or scraping or leveling delivery of a load.

Fig. 4 is an additional view of the same scraper, but showing parts in that relative position which they might occupy after a sudden dumping.

Fig. 5 is a side elevation of an alternative form hereinafter described.

Referring to the details of that specific form of my invention illustrated in Figs. 1 to 4 inclusive, 1 is a scraper bowl, which may be similar to the bowl used in a "Fresno" scraper but which is provided with arcuate shoes 2, which may be bolted or otherwise secured thereto in such manner as to give the ends of the bowl a substantially circular outline, except as the flatness of the bottom 3 of the scraper bowl may be regarded as an interruption of the mentioned circular outline; and this bowl is provided with pivots 4, which may be substantially at the center of curvature of the shoes 2, these pivots being adapted to provide a point of attachment for a main frame, by which my scraper may be drawn by a tractor, or the like.

Although various alternative constructions might be employed, I prefer to form the mentioned main frame from a pair of bent draft members 5, whose inner front ends 6 may be secured together and to a hitch plate 7 (secured also by diagonal straps 7^a), their outer rear ends 8 being shown as bent into parallel planes and as spaced apart by a brace 9, adapted to withstand horizontal stresses and of such length

as to permit of the interposition of operating parts between the respective ends of the scraper bowl and the mentioned parallel outer portions of the main frame, which may be provided with circular or slotted openings 10, to receive the pivots 4, upon the ends of said scraper bowl.

In order suitably to control the position of the bowl 1 relatively to the described main frame, I may provide means comprising a hand lever 11, shown as pivoted at 11^a near the front of the main frame and within reach of the driver of a tractor by which my scraper may be drawn, this lever being shown as connected by a rod 12 with an intermediate lever comprising as its fulcrum the rock shaft 13, shown as extending through bearing openings 14 in the parallel portions 8 of the main frame and as steadied by bearing arms 15, secured to the brace 9, one arm 16 of the mentioned intermediate lever being fixed to the rock shaft 13 and pivoted to the connecting rod 12 and the other arms 17 thereof being shown as fixed on the ends of the rock shaft 13 and pivoted to straps 18 and as provided with cam surfaces 19, adapted to engage a locking arm 20, to control the position thereof.

As will be best understood from an inspection of Figs. 2, 3 and 4, each locking arm 20, pivoted at 21 upon or adjacent to the main draft frame of my scraper, is provided at its free end with means such as a notch 22, adapted to be engaged with or disengaged from pins or projections 23, 24, angularly spaced apart upon the respective ends of the scraper bowl, resilient positioning means such as the spring 25, shown as secured to said locking arm and to the main frame of my scraper, being employed normally to hold each arm 20 in engaging position. Each locking arm 20 being provided with an offset or equivalent engaging surface 26, with which the cam surface 19 of the arm 18 may have a sliding contact, it will be obvious that the rearward movement of the hand lever 11 may be effective to throw both of the locking levers 20 out of engagement with the respective projections 23, although an immediate release of the hand lever 11 may permit a prompt engagement of the notches 22 therein with the pins or projections 24, after the bowl of my scraper shall have rotated to the gradually dumping position shown in Fig. 3, the further advance of the scraper being then effective to distribute a load over a somewhat extended area; whereas, when backward pressure is continued upon the lever 11, the bowl may be permitted to pass beyond the position shown in Fig. 3 into such a quick dumping position as is shown in Fig. 4, an immediate and complete dumping being thereby effected.

After a load has been dumped, the parts of my scraper may be permitted to advance to the relative positions shown in Fig. 4, in which my scraper may be dragged empty for any desired distance, it being understood that, after the arms 20 shall again snap into engagement with the projections 23, the bowl is held and drawn forward largely by the engagement of the said projections in the notches 22, a short horizontal slot 27 being preferably provided at one end of the strap 18, having a pivotal connection with the arm 17 and with the scraper bowl, in order that, as my scraper is drawn over uneven ground, the bottom of the bowl may conform to and slide over the undulations in the ground, without necessarily cutting the tops off from high spots or filling the low spots encountered during the advance of my scraper.

When a new load is to be picked up, it is necessary that the leading edge 28 of my scraper shall be given a downward inclination; and it is an important feature of the described construction that a forward movement of the hand lever 11 may be immediately effective to cause a suitable tilting of the bowl of my scraper, for the reason that the elevation of the normally horizontal arm 17 of the intermediate lever comprising rock shaft 13 is effective, through strap 18, to advance the pivots 4 upon which the said bowl is mounted, tipping the entire bowl forward upon the projections 23, as pivots, the drag of the load picked up by the scraper being immediately effective, as soon as the handle 11 is released, to restore all parts to the normal position shown in Fig. 2.

Especial attention is called to the shifting of the draft line from the pivot 4 to the pins 23 when the bowl rotates and the bottom 3 starts to dig into the ground to pick up a load. At this time the pressure against the cutting edge of the bottom 3, which is slightly below the pins 23, will throw the bowl, including the pivots 4, forwardly in slots 10, and as soon as the cutter picks up a load the load will move backwardly over the bottom 3 and upwardly into the bowl and the weight of the load will move the pivots 4 backwardly in the slots 10, thus bringing the bottom 3 to a level position.

Especial attention is further called to the fact that there is a primary draft rigging leading to the pivots 4 and a secondary draft rigging leading to the pins 23 and manually operative means for shifting the load from the primary draft rigging to the secondary draft rigging at the time the cutter is to dig into the ground. One object is to get the line of draft direct to the cutter at the time the cutter is doing the hard work.

It is believed that all essential features

of construction and all intended modes of operation of a scraper of the described construction will be understood from the foregoing; but it should be distinctly understood 5 that my invention is not limited thereto, one of many possible alternative embodiments of my invention being illustrated in Fig. 5. In that embodiment of my invention last referred to, the bowl and the main 10 frame being of the general character already described, an intermediate lever and a locking arm of somewhat different construction and operation are employed, the said intermediate lever having as its fulcrum a rock shaft 13^a, from which one arm 16^a normally extends upwardly and rearwardly into pivotal connection with a horizontal actuating rod 12^a, the other arm 17^a of said intermediate lever being shown as 15 projecting upwardly and forwardly into pivotal connection with one end of a curved locking arm 20^a, provided with a notch 22^a, adapted to engage projections 23, 24, and normally held in engaging position by 20 resilient means such as the spring 25. The upward movement of the free end of the locking arm 20^a being limited either by contact with a projection 23, 24, or by its contact, at 29, with a downwardly projecting 25 portion 30 of the said intermediate lever, when this last described construction is employed, it will be obvious that, as before, a slight rearward movement of the handle 11 may be effective to cause a disengagement 30 of the said locking arm from projections 23 or 24, to cause the dumping of a load in either of the manners above described; and also that a forward movement of the hand lever 11 may be effective, as before, 35 to cause a downward tilting of my scraper bowl, to pick up a load, the bowl being in this case tilted upon its pivots 4, and the locking arms 20^a being moved backward in the general direction of their length. As 40 will be appreciated upon an inspection of Fig. 5, the linear relationship between the pins 23 and the pivots 31, by which the intermediate lever is connected to the locking arm 20^a, the rock shaft of this intermediate lever being normally below a line connecting the said pins and the said pivots, the parts referred to may be regarded as 45 normally self-retaining in the positions shown, although, as before, some play may 50 advantageously be permitted, as by providing a short horizontal slot 32 in one or the other of the elements connected by the pivot pin 31.

Although I have herein described two 55 alternative embodiments of my invention, it should be understood that various features of my invention may be independently employed, and also that various modifications may be made therein, without departure from the spirit and scope of my in- 60

vention as the same is indicated above and in the following claims, and it should also be clearly understood that, although I have mentioned the bowl of the "Fresno" scraper, any similar or preferred bowl may 70 be utilized in a construction permitting the same to roll completely over and then automatically assume a position adapting it to be loaded upon the movement of a hand lever. 75

What I claim is:

1. In a rotary scraper, a bowl having one flat side with a cutting edge at the front of the flat side and having solid ends, arcuate shoes connected to the solid ends and forming substantially a circle except at the flat side of the bowl, pivots extending outwardly from the solid ends at the center of the circle of the shoes, a main frame having parallel rear ends attached to said pivots and having converging intermediate portions connected together and having parallel ends extending from the connected portions and attached to a hitch plate, a rock shaft mounted in the rear, parallel portions in front of the rotating scraper, a crank arm fixed upon the center of the rock shaft and extending upwardly, a link connected to the upper end of the crank arm and extending forwardly, a hand lever connected to the forward ends of the frame and to the link so that by operating the hand lever the rock shaft is rotated back and forth, lever arms fixed upon the ends of the rock shaft and extending substantially horizontally and backwardly and having lower cam faces, locking arms pivotally connected to the frame in front of the rock shaft and extending downwardly and backwardly and having notches in their upper faces and at their rear ends, pins fixed in the ends of the rotary scraper and adapted to engage in the notches of the locking arms, springs connecting the locking arms to the frame, and cam faces upon the locking arms to be engaged by the cam faces upon the lever arms carried by the rock shaft so that when the hand lever is pushed backwardly the cams of the lever arms will push the locking arms against the tension of the springs to release the pins from the notches in the locking arms. 110

2. In a rotary scraper, a bowl having one flat side with a cutting edge at the front of the flat side and having solid ends, arcuate shoes connected to the solid ends and forming substantially a circle except at the flat side of the bowl, pivots extending outwardly from the solid ends at the center of the circle, a frame mounted upon the pivots and extending forwardly, a rock shaft mounted in the frame in front of the rotating scraper, a crank arm fixed upon the center of the rock shaft and extending upwardly, a hand lever mounted at the forward end of the 120 125 130

frame, a link connecting the hand lever to the crank arm, lever arms fixed upon the ends of the rock shaft and extending backwardly and having lower cam faces locking arms pivotally connected to the frame in front of the rock shaft and extending downwardly and backwardly and having notches in their upper faces at their rear ends and having cams to engage the cam faces of the lever arms, pins fixed in the ends of the rotary scraper and adapted to engage in the notches of the locking arms, springs connecting the locking arms to the frame, straps pivotally mounted upon the pivots and extending forwardly and pivotally connected to the lever arms, there being means forming lost motion between the rock shaft through the lever arms and straps to the pivots, and there being means forming lost motion between the pivots and the frame.

3. In a rotary scraper, a bowl having a flat cutter and circular ends except to the extent of the flat cutter, a frame in which the bowl is rotatable mounted, two set of alined pins extending from the ends of the rotary cutter, locking arms pivotally connected to the frame and having notches to receive the pins and means for operating the locking arms to allow the scraper to rotate from one set of pins to the next.

4. In a rotary scraper, a bowl having a flat cutter and bottom and circular ends except to the extent of the flat cutter, a frame including draft members having slots, pivots extending from the ends of the bowl into the slots, locking arms pivotally connected to the frame and extending downwardly and backwardly and having notches in the upper sides of their rear ends, pins extending from the ends of the bowl and adapted to engage in the notches of the locking arms, and manual means for moving the bowl forwardly to the extent of the slots in the draft members to tilt the cutter to dig into the ground, the cutter being drawn by the locking arms and pins, and so that when the manual means is released and a load picked up the pivots will move backwardly in the slots and the cutter will assume a level position.

5. In a rotary scraper, a frame including draft members having slots, a bowl mounted between the draft members and having a flat cutter and bottom and circular ends, except to the extent of the flat cutter and bottom, pivots extending from the ends of the bowl into the slots, locking arms pivotally connected to the frame and extending backwardly and downwardly and having notches in the upper sides of their rear ends, pins extending from the ends of the bowl

and adapted to engage in the notches of the locking arms, manual means for allowing the bowl to rotate to bring the pins into the notches, manual means for moving the bowl forwardly with the pivots sliding forwardly in the slots to tilt the flat cutter and bottom, the bowl being drawn at this time by the pins in the notches, and so that when the manual means is released and a load picked up by the bottom the pivots will move backwardly in the slots and bring the bottom to a level position.

6. In a rotary scraper, a bowl having a flat cutter and bottom, means for mounting and controlling the bowl to rotate forwardly from one operation to another, and means for shifting the line of draft from the pivots of the bowl to the forward part of the cutter and tilting the cutter and bottom to pick up a load and then allowing the weight of the load to move the bowl pivots backwardly in the slots and cause the bottom to assume a level position.

7. In a rotary scraper, a bowl having a flat cutter and bottom and circular ends except to the extent of the flat cutter and bottom, and having axial pivots extending from its ends, means forming a primary draft rigging mounted upon the pivots with a limited forward and backward movement, pins extending from the ends of the bowl, a secondary draft rigging leading to the pins to be connected and disconnected, and a manually operated means for shifting the load from the primary draft rigging to the secondary draft rigging at the time the cutter is to dig into the ground so as to shift the line of draft to the cutter at the time the cutter is doing its hardest work.

8. In a rotary scraper, a bowl having a cutter and bottom, pivot pins extending from the axial centers of the ends of the bowl, means forming a primary draft rigging connected to the pivot pins with lost motion, means forming a secondary draft rigging, pins extending from the ends of the bowl and adapted to lock and unlock with the secondary draft rigging, and manual means for shifting the load from the primary draft rigging to the secondary draft rigging.

9. In a rotary bowl, means forming a rotary scraper element, a primary draft rigging connected to the scraper element, a secondary draft rigging, and manually operated means for shifting the line of draft from the primary draft rigging to the secondary draft rigging.

In testimony whereof I have signed my name to this specification.

ROE C. HAWKINS.
